UNITED STATES PATENT OFFICE.

FREDERICK J. LOUDIN, OF RAVENNA, OHIO.

FASTENER FOR THE MEETING-RAILS OF SASHES.

SPECIFICATION forming part of Letters Patent No. 510,432, dated December 12, 1893.

Application filed February 23, 1893. Serial No. 463,358. (No model.)

To all whom it may concern:

Be it known that I, FREDERICK J. LOUDIN, a citizen of the United States, residing at Ravenna, county of Portage, State of Ohio, have 5 invented a new and useful Window-Sash Fastener, of which the following is a specification.

This invention relates to that class of window-sash fasteners which employ a swinging 10 lever on the upper bar of the lower sash and a catch on the lower bar of the upper sash, with which catch said lever engages for fastening the window-sash.

The object of the invention is to secure 15 greater safety and convenience, and a further object is to lock the lower sash in a raised position or the upper sash in a lowered position, by means of a detachable extension to the catch; all as more particularly described 20 and claimed below.

In the drawings forming a part of this specification, Figure 1 is a broken perspective view, showing the sashes fastened, neither one being raised or lowered. Fig. 2 is a vertical section of the fastener in Fig. 1, taken on line 1—1, in Fig. 3, showing the sash locked when the lower one is raised or the upper one is lowered; and Fig. 3 is a plan view, with parts in section, on line x—x, in Fig. 2.

30 Referring to the lettered parts of the drawings A is the upper bar of the lower sash and B is the lower bar of the upper sash. To the bar B of the upper sash is attached an angled plate, C, fitting the upper and inner face of the same, and is provided with a catch, D, having an open notch, a, in the inner side, and an open, dovetailed mortise, c, in the top.

At E is an internally recessed casting, fitting the upper and inner face of the upper 40 bar, A, of the lower sash, and attached thereto, as in Fig. 2. It will be observed that that part of the angled plate C which fits against the inner face of the sash, B, is provided with a rib or prongs, which impregn into the sash, and a like portion of the internally recessed casting E is provided with a similar prong or ribs, O. The object of this is to prevent house breakers from forcing the plates by prying under the lower sash, which, but for 45 50 the prongs or ribs, O, would be liable to draw

the screws which fasten said plates to the sash.

Placed on the internally recessed casting E is a turn-cap, F, having a pendent stem, G, which loosely passes down through a hole in 55 the internally recessed casting E, said stem terminating at the lower end in a key, H.

In the interior recess of the casting E is a swinging lever, I. Through this lever I and through the bottom of the internally recessed 60 casting E is formed a key-hole, J, Fig. 3, adapted to receive the key, H, of the stem, G. The knob of the turn-cap, F, is preferably milled, as at e, in Fig. 1, to prevent the fingers from slipping when operating said turn-cap. 65

The turn-cap, F, is adapted to be raised and lowered so that when lowered, the key, H, will be partly in the key-hole in the lever I and partly in the key-hole of the internally recessed casting E, as in Fig. 2. When in 70 said position the lever is locked, so that it cannot be swung in either direction to disengage it from the catch, D. By raising the turn-cap F, bringing the key, H, entirely in 75 the key-hole of the lever I, and turning said turn-cap in either direction, the lever I can be swung out of or into the notch, a, of the catch D, the sashes being fastened, of course, when the lever I is in said notch, and unfastened when said lever is disengaged from the 80 notch.

That portion of the internally recessed casting E which fits against the inner face of the sash is provided with one or more vertical ribs, L, (two being shown in Fig. 3,) which 85 loosely fit into corresponding grooves, v, Fig. 1, of that portion of the plate C contiguous to them. These grooves and ribs may be employed or not, as desired, their object being to serve as a guide, so that the parts of the 90 fastener will register with each other, and to make it more difficult for a burglar to obtain access to the lever I, since he would have to saw through the ribs before he could saw the lever. 95

Referring to Figs. 1 and 2, P is a catch-extension, consisting of a bar having a series of notches, s, like those at a, in the catch D, and having one end formed so as to detachably fit in the mortise c, of the catch D, so as to 100

be located in an upright position, as in Fig. 2. When thus employed the upper or lower parts of the window may be opened a desired distance and fastened in the same manner as 5 when not open.

When the catch-extension, P, is not employed, it is caught into a notch, z, of the casting E, and placed horizontally on the window sash, as in Fig. 1.

Having thus described my invention, what 10 I claim as new, and desire to secure by Letters Patent of the United States, is—

1. A sash-fastener comprising the internally recessed casting for attachment to one 15 of the sashes, a swinging lever in said recess, said casting and lever being provided with key-holes registering with each other, a turn-cap provided with a key adapted for vertical adjustment in said holes and to swing the lever, and a catch-plate for attachment to the other sash and for receiving the end of the swinging lever; substantially as set forth.

2. A sash-fastener comprising the inter-

nally recessed casting for attachment to one of the sashes, a swinging lever in said recess, 25 said casting and lever being provided with key-holes registering with each other, a turn-cap provided with a key adapted for vertical adjustment in said holes and to swing the lever, and a catch-plate for attachment to the 30 other sash and provided with the notched catch for receiving the end of the swinging lever, in combination with the detachable catch-extension; substantially as set forth.

3. In a sash-fastener, a swinging lever attached to one of the sashes, in combination with a detachable catch-extension attached to the other sash; substantially as set forth.

In testimony to the foregoing I have hereunto subscribed my name in the presence of 40 two witnesses.

FREDERICK J. LOUDIN.
